OSCAR C. ARLITZ, OF NEW YORK, N. Y., ASSIGNEE TO LOVELL-McCONNELL MANUFACTURING COMPANY, A CORPORATION OF DELAWARE.

MECHANICAL HORN.

1,173,635.

Specification of Letters Patent. Patented Feb. 29, 1916.

Application filed March 3, 1911. Serial No. 611,963.

To all whom it may concern:

Be it known that I, OSCAR C. ARLITZ, a citizen of the United States, residing in the borough of Manhattan, in the city, county, 5 and State of New York, have invented certain new and useful Improvements in Mechanical Horns, of which the following is a specification, reference being had therein to the accompanying drawings, which form 10 a part thereof.

My invention relates to mechanical horns, and more particularly to a type thereof employing a mechanically flexed diaphragm.

One object of my invention is to provide 15 a horn of this character wherein the diaphragm will be subjected to intermittent, variable impulses from the striker member so as to develop pulsating, siren-like sound waves by the diaphragm, and will, through 20 the eccentricity of the sound produced, increase the effectiveness of the horn as a signal of danger.

A further object is to provide a horn 25 wherein the coöperating impact member carried by the diaphragm and the rotary striker member will be so constructed and arranged as to increase the number of effective impulses imparted to the diaphragm with each rotation of the striker member, 30 thus increasing the frequency of the sound waves and, if desired, permitting a diminution in the rotative speed of the striker member.

A still further object is to provide a horn 35 of this character, embodying a rotary member having a plurality of impact surfaces thereon, wherein said member in its entirety will be automatically projected into engagement with the impact member of the dia- 40 phragm while the latter is in its normal plane and will automatically recede under the reflex action of the diaphragm so as to always be in an effective engaging plane with the diaphragm, irrespective of the frequency or degree of flexure or reflexure of 45 the diaphragm.

A still further object is to provide in a 50 horn of this character, means whereby the maximum automatic adjustment of the striker member may be regulated while the

horn is in operation to facilitate the attunement of the horn. And a still further object is to provide a horn of this character which may be inexpensively produced and which will be simple and artistic in design. 55

The invention consists primarily in a mechanical horn embodying therein such other novel features of construction and combination of parts, as are hereinafter set forth and described, and more particularly pointed out in the claims hereto appended. 60

Referring to the drawings:—Figure 1 is a side elevation of a horn embodying my invention in its preferred form, the horn casing being shown in section to disclose the 65 arrangement of the actuating mechanism; Fig. 2 is a detailed view of the impact member carried by the diaphragm; Fig. 3 is a projected view of the impact member shown in Fig. 1; Fig. 4 is a fragmentary view of 70 a horn embodying a modified form of my invention, whereby the striker member is caused to automatically adjust itself to its effective operative plane; Fig. 5 is a projected view of the striker mechanism shown 75 in Figs. 4 and 6; Fig. 6 is a still further modification of the invention, the horn casing being shown in section.

Like letters refer to like parts throughout the several views. 80

In the preferred form of my invention shown in the drawings, *a* indicates a casing, the forward end of which is provided with a plate *b* having a sound outlet opening 85 therein at *c*. Projecting from the plate *b* is an ordinary amplifier or horn *d*. Mounted within the forward end of the casing *a*, adjacent to the plate *b* and spaced away therefrom, is a diaphragm *e* preferably composed of metal, although any other desired material which will withstand wear and the flexing thereof with high frequency may be used. The casing *a* has mounted therein an electric motor *f* of any desired or known construction, the armature *g* of which has 90 axial movement relative to the field magnets so as to permit axial movement of the shaft *f'* of said motor. Within the casing *a*, forwardly of the motor *f*, is a partition *a'* carrying ball bearings *a''* for the shaft *f'*. 95 100

Carried by the forward end of the shaft f' is a striker member comprising a disk h having a plurality or sequence of impact members h' preferably four in number, as shown in the projection of this member illustrated in Fig. 3, said disk h being set upon the shaft f' by means of the set screw h^3 an arrangement which permits said disk to be adjusted upon its shaft in assembling to bring the impact members h' into the desired initial plane relative to the diaphragm.

The diaphragm e carries centrally thereof, a wear or impact plate i , having thereon a plurality of projecting impact studs or members i' projecting radially of the plate i and projecting from the diaphragm in a manner to bring them within the operative plane of the impact or striker members h' upon the rotary striker member. The number of the impact surfaces i' and striker impact surfaces h' is dissimilar, thus causing each said striker impact during each cycle of said shaft f' to engage each said diaphragm impact with a resultant increase in the frequency of the flexure of the diaphragm with each rotation of said shaft to a multiple of the said impacts. This not only permits an increase in the frequency of the impulses imparted to the diaphragm, with each rotation of the striker member, but permits any desired frequency of flexure or vibration impulses with a minimum number of rotations of the rotary striker member, thus resulting in a conservation of the energy required to operate the horn.

Closing the rear of the casing a is a back plate j carrying, in the preferred form of the invention, an axially adjustable thrust bearing j' for the shaft f' . About the bearing j' is a housing j^2 for the coiled spring j^3 acted upon by an adjustment member such as the screw j^4 carried by the said housing. By this construction, the shaft f' in its entirety is normally thrust forward within the initial operative plane established in assembling the device, the tension of the spring j^3 determining the force of the impact members h' and i' and permitting the shaft f' and the striker member to recede with the reflex action of the diaphragm and to automatically assume an effective operative plane which will permit said diaphragm to freely vibrate upon both sides of its normal plane. The adjustment member j^4 permits the regulation of the tension of the spring j^3 so as to determine the force of the impact and permit the variation thereof while the horn is in operation so that the note may be determined or the horn tuned while it is running. This construction permits all of the striker impacts h' to be projected simultaneously and to simultaneously recede with the reflex action

of the diaphragm so that each striker impact h' is always in position to engage the next operative diaphragm impact i' . While I prefer this construction as presenting great refinement in construction and adjustment, the main results may be accomplished in other ways, which I have shown in modified forms of the invention in the drawings, and will hereinafter describe.

In diaphragm horns heretofore made, the note or pitch of the horn has been uniform so long as the rotary striker member had the same number of revolutions per minute. In my present invention, I provide for a pulsating or siren-like note by so constructing and arranging the coöperating impact surfaces upon the striker and the diaphragm as to cause the engagement of successive impact members to flex the diaphragm to a variable extent with a resultant variation in the displacement of air and in the tone or pitch of the note produced. The striker impacts h' are arranged concentrically of and spaced away from the axis of the shaft f' and at the same radial distance from said axis about a plane parallel with the diaphragm. To secure a variable flexure of the diaphragm, I make the diaphragm impact members i' of different lengths so that the members h' will act in succession at varying distances from the axis of the diaphragm thus resulting in a different degree of flexure, varying from a slight flexure from the shortest diaphragm impact, to a considerably greater flexure from the longest of such impacts. This arrangement results in the development of the pulsating note above referred to, due to the predetermined variation in the degree of flexure of the diaphragm through the coöperation of the impact members upon the striker member and upon the diaphragm.

In the preferred form of the invention, the axis of the shaft f' may be alined with that of the diaphragm by reason of the employment of a plurality of diaphragm impact members i' . In the modification shown in Figs. 4 to 6, however, the shaft f' is offset as to the axis of the diaphragm and said diaphragm is provided with a single wear stud or impact member i^2 secured centrally thereof. The pulsating or siren-like effect, in the modifications shown in the figures above referred to, is produced by making the striker and the impacts h^2 of different heights, which has the effect of flexing the diaphragm to a variable extent in the same manner as the construction shown and described in connection with the preferred form of my invention.

The general arrangement of the impact members h^2 in Figs. 4 and 6, is the same as in the preferred form of the invention, comprising a sequence of teeth or impact mem-

bers arranged on a plane parallel with the diaphragm concentrically about and spaced away from the axis of rotation and at the same radial distance therefrom, and one manner of arranging the teeth to secure the pulsating effect is illustrated in the projected view (Fig. 5) of one of the striker members shown in Figs. 4 and 6.

The construction differs from that shown in the preferred form as to the means varying the force of the impact in the following respect: The spring j^5 , having the same functions as the spring j^3 in the preferred form of the invention, is located between the disk h and the partition a' , the adjustment member j^4 serving solely to limit the return movement of the shaft f' under the reflex action of the diaphragm.

In the modification shown in Fig. 6, I combine in one structure the coöperating impact mechanisms shown in the modification illustrated in Figs. 4 and 5 with the thrust mechanism shown in Fig. 1, the operation of the modification shown in this figure being the same in all respects as in both of the other forms.

The operation of the preferred form of the invention is substantially as follows:—When the circuit to the motor is closed, the shaft f' thereof and the disk h and impact members h' thereon are rotated rapidly, each member h' engaging successively the diaphragm impact members i' , and flexing the diaphragm. The spring j^3 controls the force of the blow, the resistance of the diaphragm not being sufficiently great to overcome the tension of said spring. If, however, upon the reflex action of the diaphragm, one of the diaphragm impact members engages one of the striker impacts h' , it will carry all of the impact members h' rearwardly and simultaneously within the casing a against the tension of the spring j^3 until this rearward movement is checked by the member j^4 . As each impact member h' flexes the diaphragm in this manner, it will be readily observed that the diaphragm is thus flexed twelve times with each rotation of the shaft f' , said number of flexures being capable of being increased by a multiplication of the impact members and the preservation of the relative disproportionate number of such upon the diaphragm and the rotary striker.

Assuming that one of the teeth h' first engages the shortest diaphragm impact member i' , this same tooth in its impacts with the successive members i' will repeatedly flex the diaphragm with a gradually increased degree of flexure, thus gradually increasing the pitch of the note produced. Each of the impact members h' will operate in the manner I have above described, the result being an eccentric, pulsating or siren-like note. All of the impact members

h' receding simultaneously, it will be observed that the relative position of the diaphragm and the striker member is always such as to secure the desired impact between the coöperating impact members, said striker member having a normal forward thrust.

70

The operation of the modification shown in Figs. 4 to 6 is substantially like that heretofore described, except that the height of the impact members h^2 and h^3 varies the degree of flexure of the diaphragm.

75

It is not my intention to limit the invention to the precise details of construction shown in the accompanying drawings, it being apparent that such may be varied without departing from the spirit or scope of the invention.

I believe it to be broadly new to provide a mechanical horn wherein means are provided for varying the degree of flexure of the diaphragm by successive impacts upon a rotary striker member, and I intend to claim such broadly. I also believe it to be broadly new to provide a mechanical horn employing a plurality of striker impacts rotating upon a plane parallel with the plane of the diaphragm, wherein said striker impacts successively engage the dissimilar number of diaphragm impacts to multiply the number of flexures of the diaphragm with each rotation of the rotary striker member.

Having described my invention, what I claim as new, and desire to have protected by Letters Patent, is:

1. A mechanical horn embodying therein a diaphragm, an impact member carried thereby, a motor, the shaft of which is at an angle to the diaphragm and adapted to have axial movement toward and from the diaphragm, a striker member carried by said shaft and adapted to engage said impact member, means normally imparting a thrust to said shaft toward said diaphragm comprising a movable thrust bearing acting upon said shaft, a housing inclosing said bearing, an adjustment member movable in said housing and accessible exteriorly of the horn, and a spring interposed between said bearing and said adjustment member whereby the force of impact may be regulated and the effective displacement of said striker member upon the reflex action of said diaphragm may be controlled while the horn is running.

2. A mechanical horn, embodying therein a diaphragm, an electrical motor, and means for applying the power of said motor to vibrate said diaphragm, comprising an armature shaft element for said motor perpendicular to said diaphragm at its center, a diaphragm actuating element carried by said shaft, and a resilient member acting upon said shaft to normally thrust it to-

ward said diaphragm, whereby said diaphragm actuating element is always held in engagement with said diaphragm, while being capable of yielding under the reflex 5 action thereof.

3. A mechanical horn, embodying therein a diaphragm, and mechanical impact means for agitating the same, including a high speed driving shaft, disposed at an angle 10 to the diaphragm, an impact member carried by said shaft, and a resilient member acting upon said shaft to normally thrust it toward said diaphragm whereby said impact member is always held in engagement with said diaphragm, while being capable of yielding under the reflex action thereof.

4. A mechanical horn, embodying therein a diaphragm, and mechanical impact means 20 for agitating the same, including a high speed driving shaft disposed in alinement with the axis of the diaphragm, an impact member carried by said shaft, and a resilient member acting upon said shaft to normally thrust it toward said diaphragm whereby said impact member is always held in engagement with said diaphragm, while being capable of yielding under the reflex action thereof.

30 5. A mechanical horn, embodying therein a diaphragm, and mechanical impact means for agitating the same, including a rigid high speed rotary driving shaft, an impact member carried thereby, and a resilient 35 member acting upon said shaft to normally thrust it toward said diaphragm whereby said impact member is always held in engagement with said diaphragm, while being capable of yielding under the reflex action thereof.

40 6. A mechanical horn, embodying therein a diaphragm, and mechanical impact means for agitating the same, including a rigid high speed rotary driving shaft capable of 45 endwise movement, an impact member carried thereby, and a resilient member acting upon said shaft to normally thrust it toward said diaphragm whereby said impact member is always held in engagement with 50 said diaphragm, while being capable of yielding under the reflex action thereof.

55 7. In a horn or signal device, a diaphragm, a motor having a longitudinally adjustable armature shaft arranged at right-angles to the diaphragm at its center, a spring normally thrusting said shaft toward said diaphragm, and diaphragm actuating elements carried by said armature shaft, whereby relative adjustment of the 60 diaphragm and diaphragm actuating elements may be effected.

8. In a horn or signaling device, a diaphragm, means for mechanically agitating the diaphragm, including a motor having

its armature shaft arranged at an angle to 65 the diaphragm, a spring normally thrusting said shaft toward said diaphragm, diaphragm actuating means carried by said shaft, and means for effecting axial relative adjustment of the field and armature of said 70 motor.

9. In a horn or signal, a diaphragm, a power shaft approximately normal to the diaphragm, a spring normally thrusting said shaft toward said diaphragm, a rotary 75 head carried by said shaft and a plurality of diaphragm displacing elements carried by said head and distributed about the axis thereof together with a plurality of circularly distributed coöperating elements on 80 the diaphragm, whereby displacing efforts are applied at a plurality of points away from the center of the diaphragm.

10. In a horn or signal, a diaphragm, a symmetrical case arranged with its axis 85 perpendicular to said diaphragm, an electric motor and means for applying the power of said motor to vibrate said diaphragm, said means comprising an armature shaft element for said motor having its 90 axis perpendicular to said diaphragm at its center, a spring normally thrusting said shaft toward said diaphragm, and a diaphragm engaging element carried by said shaft, said diaphragm being provided with 95 a plurality of inequalities adapted for lateral engagement by said diaphragm engaging element.

11. A mechanical horn, embodying therein a diaphragm, an impact member carried 100 thereby, a shaft at an angle to said diaphragm and movable axially, a spring normally tending to thrust said shaft toward said diaphragm, a rotor mounted on said shaft to coöperate with said impact 105 member and vibrate said diaphragm whereby said rotor will automatically recede against the action of said spring upon the reflex action of said diaphragm, and said rotor will always rotate upon an effective 110 operative plane irrespective of the degree of flexure or reflexure of said diaphragm.

12. A mechanical horn, embodying therein a diaphragm, an impact member carried thereby, a shaft at an angle to said diaphragm and movable axially, a spring 115 normally tending to thrust said shaft toward said diaphragm, a rotor mounted on said shaft to coöperate with said impact member and vibrate said diaphragm whereby said rotor will automatically recede against the action of said spring upon the reflex action of said diaphragm, and said rotor will always rotate upon an effective 120 operative plane irrespective of the degree of flexure or reflexure of said diaphragm, and means regulating the tension of said spring 125 whereby the force of said thrust and the

effective displacement of said rotor upon the reflex action upon said diaphragm may be controlled.

13. A mechanical horn, embodying there-
5 in a diaphragm, having an impact member presenting a plurality of impact surfaces, extending radially to different distances, and a rotary striker member at right angles to said diaphragm, and having a plurality
10 of impact surfaces having successive en-

gagement with said first-mentioned impact surfaces.

In witness whereof, I have hereunto affixed my signature, in the presence of two witnesses, this 25th day of February, 1911. 15

OSCAR C. ARLITZ.
